US0D1074312S

(12) **United States Design Patent** (10) **Patent No.:** **US D1,074,312 S**
Nwosu (45) **Date of Patent:** **** May 13, 2025**

(54) **THERMAL FLASK**

(71) Applicant: **Arizechukwu Nwosu**, Westlake Village, CA (US)
(72) Inventor: **Arizechukwu Nwosu**, Westlake Village, CA (US)

(**) Term: **15 Years**

(21) Appl. No.: **29/913,536**

(22) Filed: **Oct. 4, 2023**

(51) **LOC (15) Cl.** **07-01**

(52) **U.S. Cl.**

USPC **D7/511**

(58) **Field of Classification Search**

(57) **CLAIM**

The ornamental design for a thermal flask, as shown and described.

DESCRIPTION

FIG. 1 is a front view of a thermal flask showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof; and,

FIG. 8 is a bottom perspective thereof.

1 Claim, 8 Drawing Sheets
